UNITED STATES PATENT OFFICE

BERT O. RHODES, OF KALAMAZOO, MICHIGAN

DISPENSING CAN

Application filed June 17, 1929. Serial No. 371,646.

The main object of this invention is to provide an improved dispensing can by means of which relatively heavy liquids such as lubricants may be effectively poured or discharged from the receptacle into a crank case or the like at the desired speed.

A further object is to provide a structure of this character which may be filled through the spout by means of a force pump or the like.

Objects relating to details and economies of my invention will appear from the description to follow. The invention is defined in the claims.

A structure which is a preferred embodiment of my invention is illustrated in the accompanying drawings, in which:

Fig. 1 is a side elevation of my improved dispensing can.

Fig. 2 is a fragmentary view in vertical section on line 2—2 of Fig. 1.

Fig. 3 is a perspective view of the spout portion of the can prior to assembling or mounting in the can.

Fig. 4 is a fragmentary vertical sectional view corresponding to that of Fig. 2 of a slightly modified construction.

Referring to the drawings, 1 represents a receptacle which is in practice designed to hold a given definite quantity of lubricant, usually a quart. This receptacle is provided with a threaded neck 2. A cap 3 which is commonly a stamping is provided with a threaded portion 4 at its lower end engaging the neck and has a shoulder 5 above the threaded portion providing a gasket seat.

The cap has a central opening in the top thereof provided with an inturned seam flange 6. The spout 7 is provided with an out-turned seam flange 8 which is interlocked with the seam flange 6. In practice the seam flanges are turned on the edges of the cap opening and the lower edge of the spout, the spout inserted, and the parts forced together, interlocking the seam flanges.

The upper end of the spout is folded downwardly upon itself at 9 providing a reinforce for the nose of the spout and also providing a smooth edge for the spout. This permits the spout being formed of very light material.

The edge is reinforced so that it is not likely to be distorted in handling by striking against the parts of an engine, for instance; and, further, as stated, a smooth edge is provided.

The spout is formed by rolling a piece of metal of suitable shape upon a mandrel, the edges being secured together by a vertical seam 10.

The cap is provided with a vent opening 11 preferably located close to the shoulder, while the spout is provided with a tongue-like baffle member 12 having an out-turned end 13 disposed between the shoulder 5 and the gasket 17. This baffle member is preferably downwardly inclined, as indicated, and disposed in front of or in alignment with the vent opening.

On the filling of the receptacle through the spout as by means of a force pump, the liquid is prevented by the baffle from passing out through the opening 11 and any drip of the spout which might otherwise reach the vent is deflected therefrom by the baffle. On the emptying of the receptacle the baffle and the inrush of air through the vent effectively prevent any liquid from escaping through the vent, even though the can be completely inverted. The baffle is quite narrow so that the air can pass directly into and from the receptacle. Were a wide baffle to be used it would, in effect, constitute a tube into which sufficient of the liquid would enter to cause gurgling as the liquid is poured from the spout. I have found that by employing a relatively narrow baffle gurgling is eliminated.

In the modification shown in Fig. 4 the vent 14 is formed in the side of the spout, the baffle 15 corresponding to the baffle 12 being turned upwardly within the spout and soldered at 16. The structure shown in Figs. 1, 2 and 3 is preferred for manufacturing reasons, although the structure shown in Fig. 4 is quite efficient.

My improved dispensing can is very efficient in the matter of permitting rapid discharge of the liquid. It may also be quickly filled as by means of a pump, and is very economical to produce.

The embodiment of my improvements illustrated is especially designed by me for use in a dispensing can for lubricants at filling stations. The same is, however, desirable 5 for use in various other relations.

Having thus described my invention what I claim as new and desire to secure by Letters Patent is:

1. A dispensing can comprising a receptacle, a cap therefor provided with a downwardly facing gasket seat and having a spout opening provided with an inturned seam flange and a vent located between said gasket seat and spout opening, a gasket arranged on 10 said gasket seat to coact with the end of the neck, and a tapered spout having an upturned seam flange at its lower end interlocking with said inturned seam flange of said cap, said spout having a tongue-like baffle depending 15 from its lower end disposed between said gasket seat and gasket.

2. A dispensing can comprising a receptacle, a cap therefor having a spout opening provided with an inturned seam flange and a 25 vent, and a tapered spout having an upturned seam flange at its lower end interlocking with said inturned seam flange of said cap, said spout having a tongue-like baffle depending from its lower end in 30 opposed relation to said vent.

3. A dispensing can comprising a receptacle, a cap therefor provided with a downwardly facing gasket seat and having a spout opening therein and a vent located between 35 said gasket seat and spout opening, a gasket arranged on said gasket seat to coact with the end of the neck, and a spout secured in said spout opening and having a tongue-like baffle depending from its lower end in 40 opposed relation to said vent and with its lower end disposed between said gasket seat and gasket.

4. A dispensing can comprising a receptacle, a cap therefor having a spout opening 45 therein and a vent, and a spout secured in said spout opening and having a tongue-like baffle on its lower end disposed in opposed relation to said vent, the upper end of the 50 spout being folded downwardly upon itself to reinforce the nose of the spout and provide a smooth edge therefor.

5. A dispensing can comprising a receptacle, a cap having a spout opening therein provided with an inturned seam flange, and 55 a spout having an out-turned seam flange at its lower end interlocking the said inturned seam flange of said cap, said spout having an integral tongue-like baffle member on its lower end, there being a vent opening in 60 alignment with said baffle member.

6. A dispensing can comprising a receptacle, a cap having an opening in the top thereof, and a spout secured in the said opening and provided with an integral outwardly 65 inclined narrow tongue-like baffle depending

into the cap, said cap being provided with a vent opening in alignment with said baffle.

7. A dispensing can comprising a receptacle, a cap therefor provided with a vent opening and with a spout, and a narrow tongue-like baffle member depending from 70 said spout in alignment with said vent opening.

8. A dispensing can comprising a receptacle, a cap therefor provided with a spout, 75 said spout having a narrow integral tongue-like baffle, and a vent opening in the cap disposed in alignment with said baffle.

9. A dispensing can comprising a receptacle, and a cap therefor provided with a spout having an integral tongue-like baffle formed as an extension of its lower end, there 80 being a vent opening opposite said baffle.

In witness whereof I have hereunto set my hand.

BERT O. RHODES.
